Attorney, Agent, or Firm—Foley & Lardner

[73] Assignee: Newell Operating Company, Freeport,
Ill.

[57] **CLAIM**

[**] Term: 14 Years

I claim the ornamental design for a knob, as shown and
described.

[21] Appl. No.: 29/118,036

DESCRIPTION

[22] Filed: Feb. 3, 2000

FIG. 1 is a perspective view of the knob according to a
preferred embodiment.

[51] LOC (7) Cl. 08-06

FIG. 2 is a top plan view of the knob.

[52] U.S. Cl. D8/310

FIG. 3 is a front elevation view of the knob; and,
FIG. 4 is a bottom plan view of the knob.

[58] Field of Search D8/300-302, 307,
D8/310; D23/250-254; 16/414, 417, 441,
110.1

The broken lines at the base of the stem represents the
bounds of the claim and all others are for illustrative
purposes only. None of the broken lines form a part of the
claimed design.

[56] **References Cited**

The surface(s) or portion(s) of the article not shown in the
drawing or described in the specification form(s) no part of
the claimed design.
